UNITED STATES PATENT OFFICE.

PAUL FRIEDMAN, OF CURTICE, OHIO, ASSIGNOR OF ONE-THIRD TO LENA ABERL, OF OREGON TOWNSHIP, OHIO.

MERRY-GO-ROUND.

SPECIFICATION forming part of Letters Patent No. 727,778, dated May 12, 1903.

Application filed December 12, 1902. Serial No. 134,884. (No model.)

To all whom it may concern:

Be it known that I, PAUL FRIEDMAN, of Curtice, county of Ottawa, and State of Ohio, have invented certain new and useful Improvements in Merry-Go-Rounds; and I do hereby declare that the following is a full, clear, and exact description of the invention, which will enable others skilled in the art to which it appertains to make and use the same, reference being had to the accompanying drawings, and to the figures of reference marked thereon, which form a part of this specification.

My invention has reference to a merry-go-round of simple and novel construction which may be readily set up in any convenient place, either indoors or out of doors, and as readily taken apart for the purpose of storing away.

The device is especially adapted for the entertainment and exercise of small children, and is arranged with attachable arms, each carrying a seat to accommodate a varying number.

In carrying out my invention I employ certain novel features of construction and the arrangement of the parts hereinafter shown, described, and claimed.

In the drawings, Figure 1 is an elevation of my invention, and Fig. 2 is a plan view showing the arrangement of the detachable arms with reference to the rotatable head.

Referring to the parts, 1 is a ball-bearing or roller-bearing head, the same comprising a stationary disk member 2 and a rotatable disk member 3, between which balls or rollers are arranged in suitable raceways to permit the easy rotation of the member 3. The member 2 is provided with a socket 4 for attachment to a vertical support 5.

40 Detachably secured to the rotatable member 3 are a plurality of radially-extending arms 6, formed out of flattened bands of spring-steel. Arranged annularly about the center of the rotatable member 3 are a plurality of inverted-U-shaped loops 7, adapted to receive the ends of the arms 6. The loops 7 are preferably of wrought-iron and may be cast into the body of the member 3, or the same may be made to extend through vertical perforations in the member 3 and held in posi-

tion by means of nuts in contact with the lower face of said member. There are also formed upon the member 3 a plurality of upwardly-extending radial ribs 8, arranged about the periphery of said member and adapted to maintain the arms 6 in position between them. The inner ends of the arms 6 are formed with an upward bend 9 to hold the same from sliding outward by centrifugal action when the device is in operation. One 60 of the spring-arms 6 is bent, as shown in Fig. 1, being formed with a right-angled bend 10 and at its lower end with a return-bend 11, and 12 is a frame at the outer end of said arm, in which is rotatably mounted a pedal-wheel 13. The frame 12 is provided with a saddle and handle-bar, as shown. The other arms 6 extend radially outward and are provided at their ends with seats. By the arrangement shown one seat only may be provided or any number of additional seats, the device as illustrated being, however, limited to seven seats. To detach the arms on which the seats are secured, the outer ends thereof are simply raised to disengage the curved 75 ends 9 from the loops 7. At 14 I have shown sections or segments of a circular runway or track, on which the pedal-wheel 13 is adapted to travel. This runway is, however, not an essential requirement of my invention and 80 may be dispensed with, since the device when in use out of doors may be operated upon any suitable level surface. The arms 6 being resilient, the seats will spring up and down when the same are occupied, and contact of the 85 pedal-wheel with the runway is insured. The novel formation of the arm supporting the pedal-wheel permits operation of the pedal-wheel without interference.

The utility of my invention as an exercising device for children is apparent.

Having described my invention, what I claim, and desire to secure by Letters Patent of the United States, is—

In a merry-go-round, a rotatable head comprising a stationary disk member secured at the upper end of a support, and a rotatable member mounted so as to revolve upon said stationary member, the annularly-arranged loops 7 and the ribs 8 upon the rotatable mem- 95 100.

ber, and radially-extending resilient arms having their inner ends upturned to enter and engage the loops 7, and to rest in position between the ribs 8, one of said arms having 5 the bends 10 and 11 and a pedal-wheel mounted at its outer end, the other of said arms having seats at their free ends, as set forth.

In testimony that I claim the foregoing as my own I affix my signature in presence of two witnesses.

PAUL FRIEDMAN.
